US0D1053225S

(12) **United States Design Patent** (10) Patent No.: **US D1,053,225 S**
(45) Date of Patent: ** *Dec. 3, 2024

(54) **ROUNDED EDGE COOLER CABINET DESIGN**

(71) Applicant: **Innovative Display Works, Inc.**, Rancho Cucamonga, CA (US)

(72) Inventors: **Jerald Joseph Foster**, Rancho Cucamonga, CA (US); **Matthew John Maulucci**, Rancho Cucamonga, CA (US)

(73) Assignee: **INNOVATIVE DISPLAYWORKS, INC.**, Rancho Cucamonga, CA (US)

(*) Notice: This patent is subject to a terminal disclaimer.

(**) Term: **15 Years**

(21) Appl. No.: **29/885,662**

(22) Filed: **Feb. 27, 2023**

(51) LOC (14) Cl. **15-07**

(52) U.S. Cl.

USPC **D15/81**

(58) **Field of Classification Search**

USPC D15/79-91

CLAIM

The ornamental design for rounded edge cooler cabinet design as shown and described.

DESCRIPTION

FIG. 1 is a front perspective view of the cooler of the present invention showing our new design;

FIG. 2 is a front view thereof;

FIG. 3 is a right-side view thereof;

FIG. 4 is a left-side view thereof;
FIG. 5 is a rear view thereof;
FIG. 6 is a top plan view thereof;
FIG. 7 is a bottom plan view thereof;
FIG. 8 is a front perspective view of a second embodiment of the cooler of the present invention;
FIG. 9 is a front view thereof;
FIG. 10 is a right-side view thereof;
FIG. 11 is a left-side view thereof;
FIG. 12 is a rear view thereof;
